United States Patent Office

Des. 178,605
Patented Aug. 28, 1956

178,605

BUILDING PANEL

Roger A. Hield, Kansas City, Mo., assignor to Butler Manufacturing Company, Kansas City, Mo., a corporation of Missouri

Application January 27, 1955, Serial No. 34,259

Term of patent 14 years

(Cl. D54—2)

Fig. 1.

Fig. 2.

Fig. 1 is a plan view of a building panel embodying my new design, and

Fig. 2 is an end elevational view of same.

I claim:

The ornamental design for a building panel, substantially as shown.
